(57) **CLAIM**

The ornamental design for a shoe, as shown and described.

DESCRIPTION

FIG. 1 is a left side view of a shoe in accordance with an embodiment of our new design;
FIG. 2 is a right side view thereof;
FIG. 3 is a front view thereof;
FIG. 4 is a rear view thereof;
FIG. 5 is a top view thereof;
FIG. 6 is a bottom view thereof;
FIG. 7 is an end view taken along line 7-7 of FIG. 6, without an upper;
FIG. 8 is an end view taken along line 8-8 of FIG. 6, without an upper;
FIG. 9 is an enlarged view of the portion of the shoe shown within the area designated as "9" in FIG. 7; and,
FIG. 10 is an enlarged view of the portion of the shoe shown within the area designated as "10" in FIG. 8.
The broken lines shown in the figures depict portions of the shoe that form no part of the claimed design.

1 Claim, 7 Drawing Sheets
